UNITED STATES PATENT OFFICE.

FRANK G. JOHNSON, OF NEW YORK, N. Y.

COOLING AND REFRIGERATING APPARATUS.

SPECIFICATION forming part of Letters Patent No. 322,826, dated July 21, 1885.

Application filed May 1, 1885. (No model.)

To all whom it may concern:

Be it known that I, FRANK G. JOHNSON, a citizen of the United States, residing in the city, county, and State of New York, have 5 invented a new and useful Improvement in Cooling and Refrigerating Apparatuses, of which the following is a specification.

My invention relates to improvements in the manner of providing artificial refrigeration 10 for family and other uses where ice is usually employed for cooling; and it consists of a simple device whereby the cold is produced by the escape and expansion of previously condensed air within detached portable com- 15 pressed-air receivers, the said receivers while the air is escaping and expanding being deposited within the receptacle wherein the refrigeration is to be performed, as will more fully appear by reference to the accompany- 20 ing drawings, in which—

Figure 1 represents the detached portable compressed-air receiver filled with highly compressed air, preferably compressed atmospheric air; and Fig. 2, a view of an ordinary 25 double-walled box, such as is usually termed a "refrigerator" or "ice-box," showing one of the detached portable compressed-air receivers highly charged with compressed air within the upper compartment thereof, where, 30 in such boxes, is usually deposited the ice.

Similar letters refer to similar parts.

The objects of my invention are, first, to provide artificial refrigeration for family and other uses, for the preservation of fruits, vegetables, meats, milk, beer, &c., as also for the temporary preservation of corpses, by the employment of dry cold air instead of moist cold air—in other words, to provide practical artificial refrigeration for the above-mentioned 40 and other uses without the employment of ice, and so to obviate the many objections which are unavoidably attendant upon the use of ice for such purposes; second, to render refrigeration for such purposes cheaper, more 45 convenient, and more healthful; third, to render it practicably possible to obtain for such and other uses a greater degree of refrigeration than is possible by the employment of ice alone, it being practical by my invention, 50 as ascertained by experiment, to reduce the temperature in an ordinary so-called "refrigerator" down to zero, while by the use of

ice alone in the same so-called "refrigerators" it is practical to reduce the temperature down to only about 40° above zero. The manner and means whereby I attain these objects are clearly described as follows:

C, Fig. 1, is a strong metallic cylinder, to be made of various sizes to suit various uses, which I term the "detached portable compressed-air receiver," which, by means of a suitable air-compressing engine, is filled with highly-compressed atmospheric air. When so filled it is detached from the compressor-engine, and allowed to stand until all the liberated latent heat, which is set free by compression of the air, passes off by radiation, when it will be ready for use. This detached portable compressed-air receiver C, thus charged and cooled down to the temperature of the surrounding open air, is now placed within the double-walled box A, or any other suitable refrigerating-receptacle where the refrigeration is required; a portion, A', of the walls of the box A, as shown in the drawings, being cut away to show the position of the receiver C; the preferable position of the receiver C within the box A being, as shown, at the upper part, where, in such boxes, the ice is usually deposited, for the reason that cold air will settle down into the lower compartment, D, where is placed the various articles to be preserved. The charged receiver C being thus placed within the interior of the refrigerating-receptacle wherein the refrigeration is to be produced, it is only necessary now to partially open the escape cock or faucet c', and thus allow the compressed air to gradually flow out of the receiver into and expand within the refrigerating-receptacle A, 90 the covers of the same to be shut down as soon as the cock c' is opened.

In Fig. 2, d d represent a tray or platform placed in the upper compartment of the receptacle A upon which to rest the receiver C.

Having thus described the several parts of my device and their relation to each other, I will now explain the operation of my invention, which is as follows: As the compressed air within the detached portable compressed-air receiver flows out through the cock c' it expands within the refrigerating-receptacle A, and by thus expanding becomes capable of absorbing and does absorb the free heat of the

air therein contained, thus reducing the temperature of the air and everything contained within the said receptacle. When the receiver C is exhausted, it is replaced by another freshly charged.

The object of placing the receiver C within the refrigerating-receptacle where it is desired to have the refrigeration take place, instead of placing it outside of the same and connecting the two together by means of a pipe through which to pass the compressed air from the receiver into the interior of the said receptacle, as set forth in my application for Letters Patent filed March 23, 1885, and numbered 159,744, which application was allowed April 2, 1885, is that, by experiment, it is found that while the compressed air is flowing out of the receiver very intense cold takes place within the receiver itself, causing the outside of it to be covered with frost, and reducing the temperature upon its outer surface down to zero; hence, by placing the receiver C within instead of outside of the refrigerating-receptacle A this very intense cold produced within the receiver is economized, and made to aid in reducing the temperature within the receptacle A, instead of being allowed to go to waste in the open air.

I am aware that the expansion of compressed air has been employed for reducing temperature when allowed to pass directly from the compressor to the apartment to be cooled, in which case the compressed air must be first and immediately cooled by cold water or other artificial means before it can be used for refrigeration.

I am also aware that in my own application

for Letters Patent, above referred to, I have claimed the use of portable compressed-air receivers in combination with so-called "ice-boxes," burial-caskets, &c., in which said application, as set forth in the specification thereof, the portable condensed-air receiver is placed outside of the receptacle wherein the refrigeration is to take place, and the receiver and the so-called "refrigerators" are attached together by a pipe, through which the compressed air passes from the receiver into the receptacle to be cooled. Therefore I do not claim, broadly, the reduction of temperature by the expansion of compressed air irrespective of the method employed; nor do I claim, broadly, the reduction of temperature by the expansion of compressed air when the method employed consists of the use of portable condensed-air receivers placed or standing outside of the receptacle wherein the refrigeration is to take place and the two are connected by passage-ways or pipes; but

What I do claim as new and useful, and desire to secure by Letters Patent, is—

For artificial refrigeration for the preservation of perishable articles, the combination of the refrigerating-receptacle A and the detached portable compressed-air receiver C, charged with compressed air, by simply placing the said charged receiver C within the said refrigerating-receptacle A, substantially in the manner and for the purposes set forth.

FRANK G. JOHNSON.
